UNITED STATES PATENT OFFICE

WILLIAM M. GOLDSMITH, OF CINCINNATI, OHIO, ASSIGNOR TO THE GOLDSMITH METAL
LATH COMPANY, OF CINCINNATI, OHIO, A CORPORATION OF OHIO

REMOVABLE METAL TILE STRUCTURE FOR FORMING CONCRETE FLOORS

Application filed February 10, 1926. Serial No. 87,408.

An object of my invention is to provide a metal tile for use in concrete floor construction and a simple and inexpensive means for mounting and positioning said tiles.

5 Another object is to provide a mounting means which is inexpensive of manufacture and simple of application.

Another object is to provide a metal tile and mounting means therefor which will permit ready removal of the tiles after the concrete floor has been poured and has become set.

Another object is to provide a mounting means for the purpose stated which is adapted for use with tiles of various sizes.

These and other objects are attained by the means described herein and disclosed in the accompanying drawings, in which:

Fig. 1 is a fragmental perspective view of 20 a structure embodying the tile and mounting means of my invention prior to the pouring of concrete.

Fig. 2 is a similar view showing a modified application of the device of my invention.

25 The metal tiles 8 are of any approved shape and are provided with sides 9 having straight bottom edges 10. The mounting means comprises angle strips 11, the sides 12 and 13 of which may be at right angles to one another.

30 As shown in Fig. 1, a suitable supporting structure comprising shoring 14, stringers 15 and soffits 16 is erected. The angle strips 11 which may be of light gauge metal, are then secured in alignment upon the opposite sides

35 of the soffits 16 by means of nails 17. The tiles 8 are then positioned between the angle strips 11 by seating the opposite longitudinal edges 10 of a given tile upon adjacent soffits, with the sides 9 of said tile in abutment with the upstanding sides 12 of the angle strips. The concrete is then poured

40 over the tiles and the space between the outer faces of the side walls 9 of the tiles is filled with concrete to form beams. It will be readily understood that suitable reinforcing elements may be positioned between adjacent tiles where required. After a floor has been

45 poured and set, the temporary supporting structure is removed whereupon the soffits 16 will be removed from the beams at which time

the longitudinal edges 10 of the tile will be exposed rendering said tiles readily accessible for removal and permitting them to be used again.

As shown in Fig. 2, the angle strips 11 are 55 positioned with a free edge disposed toward the edge of a soffit 16 and the upstanding side disposed farthest from the edge of said soffit. In this structure, the opposite sides 9 of a given tile have their longitudinal edges 10 seated upon the upper or inner face of the sides 12 of the angle strips 11 with the outer faces of the sides 9 of the tile in abutment with the upstanding side 13 of the angle strips. When a concrete floor has been 60 poured and has become set upon a supporting structure such as shown in Fig. 2, the shoring 14 and stringers 15 may be removed whereupon the sleepers 16 may be pulled down, leaving the edges 10 of the tiles exposed and thus facilitating removal of the tiles.

It should be noted that in each of the structures described, the angle strips 11 will remain secured to the soffits 16 and will be removed therewith so that the angle strips may also be used repeatedly. The angle strips 11 being light and easy to handle eliminates considerable labor and difficulty in aligning and positioning the tiles. The operation of 75 constructing a floor with the tile and angle strip material of my invention consists in simply providing guide lines along the soffits and nailing the angle strips along the guide line after which the tiles may be readily dropped into place. The upstanding side of the angle strips not only positions the sides of the tile, but also precludes spreading thereof, and when the sleepers and angles are removed, the tile is left accessible for removal. 80 It should also be noted that the angle mounting strip may be employed with hollow domes or tiles having closed sides and ends. The tiles and angle mounting strips of my invention are inexpensive of manufacture and 85 both tiles and mounting strips may be readily nested so as to occupy a minimum of space which facilitates storing, shipping and handling in addition to the advantages above 90 set forth.

What I claim is:

1. In a concrete floor in the course of erection the combination of a temporary support structure, a series of parallel rows of angle mounting strips on the temporary support structure, the angle strips each having an upwardly extending arm, the upstanding arms being disposed alternately on opposite sides of the rows of strips, whereby there are provided opposed pairs of upstanding arms, and inverted U shape tiles having the ends of their arms received between opposed pairs of upstanding arms, whereby a mold for concrete is formed and in which mold the strips are exposed to the concrete mass and the ends of the inverted U shape tiles are protected from contact with the concrete mass.
- 10
- 15

2. In a concrete floor in course of construction the combination of temporary centering, a plurality of pairs of independent rows of angle strips, the angle strips each comprising a pair of flanges, one of each of which flanges rests on and is secured to the centering and the other of which flanges extends upwardly beyond the centering for providing a pair of opposed abutment surfaces for each of said pairs of rows of strips, inverted U-shape tiles having the free ends of their arms between the opposed and upwardly extending abutment surfaces on the strips, the tiles forming joist molds between them, the concrete in the joist molds between the tiles being spaced from the free ends of the tiles by the upstanding flanges of the angle strips, whereby the free ends of the tiles may be exposed, free of the concrete, after the centering is removed.

3. In a concrete floor in course of erection, the combination of spaced soffits, angle strips arranged in spaced courses upon the soffits for providing fixed ways between adjacent courses of angle strips, U shaped tiles inverted and positioned between alternate pairs of adjacent courses of angle strips for closing the spaces between the soffits and providing spaced ways between adjacent tiles and over the soffits for receiving beam forming concrete and the angle strips engaging the tiles on the sides of the tiles exposed to the concrete for precluding spreading of the tiles under the weight of a concrete mass formed around the tiles.

4. In a concrete floor in course of construction, the combination of a temporary support structure, a series of rows of mounting strips on the temporary support structure, the strips each comprising an upwardly extending portion, the said upstanding portions being disposed alternately on opposite sides of the rows of strips, whereby there are provided opposed pairs of upstanding portions, and inverted U shape tiles having the ends of their arms received between opposed pairs of said upstanding arms, whereby a mold for concrete

is formed and in which mold the strips are exposed to the concrete mass.

5. A form structure for concrete floors comprising edgewise spaced planks, a means for supporting the same, tiles supported on the longitudinal edges of the planks and spanning the openings therebetween, and strips secured to said planks having outer faces extending parallel to and within the outer edges of said planks against which the tiles engage and which hold and position the latter, said planks and strips being removable as a unit after the concrete has set.

In testimony whereof, I have hereunto subscribed my name this 5th day of February, 1926.

WILLIAM M. GOLDSMITH.
